United States Patent Office.

LEMIR J. NEY, OF DRACUT, ASSIGNOR TO LOWELL MANUFACTURING COMPANY, OF LOWELL, MASSACHUSETTS.

Design No. 4,090, dated May 31, 1870.

DESIGN FOR A CARPET-PATTERN.

The Schedule referred to in these Letters Patent and making part of the same.

---

all whom it may concern:

Be it known that I, ELEMIR J. NEY, of the town Dracut, county of Middlesex and State of Massachusetts, have invented and produced a new and ginal Design for a Pattern to be inwrought into o-ply, Ingrain, and other Carpeting, in such colors as y be desired; and I do hereby declare that the photographic print accompanying this specification does e and convey, to any one skilled in the art of car- weaving, a more definite and thorough description the nature of my invention than it is in the power language otherwise to convey, and it is sufficient to enable any one skilled in the art of carpet-weaving to use my invention.

What I claim as my invention, and desire to se- cure by Letters Patent, is—

The configuration of the design hereunto annexed, when made by being inwrought into two-ply, ingrain, or other carpeting, in the form similar to the photo- graphic print accompanying this specification.

E. J. NEY.
